OSCILLATION GENERATOR COMPRISING
ELECTRON DISCHARGE DEVICES

George Maurice Wright and Noël Meyer Rust,
Chelmsford, England, assignors to Radio Corporation of America, a corporation of Delaware

Application October 8, 1935, Serial No. 44,046
In Great Britain August 30, 1934

2 Claims. (Cl. 250—36)

This invention relates to electrical oscillation generators comprising electron discharge devices and more particularly to tuned thermionic valve oscillation generators of the kind wherein a thermionic valve is connected in a reaction circuit for self-oscillation, i. e., is connected so that its output electrode is back coupled to its input or control electrode for the generation of sustained oscillation.

Known oscillation generators of this kind vary the frequency of the alternating current generated when the intensity of the reaction coupling is varied. Such inconstancy of frequency is often undesirable since changes in the reaction intensity made for the purpose of securing the best operation of the generator itself, or that of associated circuits, result in a frequency change which may mask the effect aimed at in making such adjustments.

The reason for such variation in frequency is that the coupling between the portions of the circuit providing the reaction results in a modification of the effective electrical constants of the path of the oscillatory current, and so when the coupling is varied, the frequency of the generated oscillations is correspondingly changed.

The invention is explained in connection with Figs. 1 and 2 of the drawing. Fig. 1 represents an example of the prior art and Fig. 2 shows the present improvement thereover.

As an example, known oscillation generators of the kind referred to may, for the purposes of the present invention, be regarded as typified by that well known oscillator circuit arrangement illustrated in the accompanying Fig. 1, wherein the anode circuit of a triode 1 is back coupled to its control grid 2 through an adjustable coupling condenser 3 connected between the said control grid 2 and the adjacent end of a parallel tuned anode oscillatory circuit 4, 5, anode potential from a source (not shown but having its positive terminal marked +HT) being applied to the anode 6 through a tapping 7 on the inductance 4 in the parallel tuned circuit 4, 5, and the control grid 2 being connected to the cathode 8 through a grid leak 9 the cathode being, of course, connected to the negative terminal —HT of the anode potential source.

Now, with this and with similar oscillator circuit arrangements, the intentions are that the frequency of the oscillations generated shall be determined by adjusting the natural frequency of the parallel tuned circuit 4, 5—the condenser 5 in this tuned circuit is generally made variable for this purpose—and the energy feed back shall

be determined by adjusting the coupling condenser 3. However, if the circuit of Fig. 1 be analyzed, it will be seen that the coupling condenser 3 is in series with the grid-anode self-capacity of the valve 1, and that these two series connected capacities are together in parallel with the parallel tuned circuit 4, 5. Accordingly, although it is intended that the frequency generated shall be determined only by the adjustment of the parallel tuned circuit 4, 5, and the reaction condition be determined only by the adjustment of the coupling condenser 3, in fact any adjustment of the coupling condenser will alter the frequency generated since this condenser (in series with the grid-anode self-capacity of the valve) is in shunt across the parallel tuned circuit. This interdependence of the adjustment means provided for control of the reaction conditions and control of the frequency is, in practice, very undesirable and the main object of the present invention is to provide an improved thermionic oscillation generator of the kind referred to, wherein adjustment of the conditions for oscillation generation can be made substantially without altering the frequency generated.

It can also be shown that other known types of reaction arrangement manifests similar modifications of the constants of the oscillatory circuit.

According to this invention, the valve employed in a thermionic oscillation generator of the kind referred to, is of the so-called "variable mu" type, and adjustment of the reaction conditions is effected substantially without affecting the frequency generated by adjusting an amplification determining potential applied to an electrode of the valve, the hitherto usual variable coupling condenser in the reaction circuit being replaced by a fixed coupling condenser or other reaction device or arrangement of predetermined magnitude.

One arrangement in accordance with this invention is shown in the accompanying Fig. 2. Here the oscillator valve 1a is of the "variable mu" type and has its anode 6a connected to its control grid 2a through a parallel tuned circuit 4, 5, which is connected at one end to said anode 6a and at the other end is connected through a fixed coupling condenser 3a to the control grid 2a. The control grid is connected to one end of a choke 10 whose other end is connected to a variable tapping point 11 upon a potentiometer resistance 12 which is shunted by a bias potential source 13. One end of the potentiometer resistance 12 is connected to the valve cathode 8a to which point the negative terminal of the

- anode potential source is also connected, the positive terminal of this source being connected to a tapping point 7 upon the inductance 4 in the parallel tuned circuit. The choke 10 which 5 is a high frequency choke, serves to prevent the potentiometer producing a high frequency short circuit path between the control grid and the cathode. The tendency of the system to oscillate is adjusted by moving the potentiometer 10 tapping point 11 upon the potentiometer resistance 12 and obviously this adjustment varies the grid bias for the valve, and, in a "variable mu" type of valve the grid bias potential is an amplification determining potential. It will be appreciated accordingly that in this improved circuit arrangement variation of the position of the potentiometer tapping point 11 will adjust the reaction conditions substantially without altering the frequency of oscillation.
- 20 Any suitable known type of "variable mu" valve can be employed in carrying out this invention, a convenient and commonly available type being that wherein the grid is constituted by an approximately helical wire winding whose 25 pitch is not constant but varies over the length of the grid.
- What we claim is:
1. An oscillation generator for generating continuous, uninterrupted oscillations of substantially constant frequency comprising an

electron discharge device of the variable mu type having an anode, cathode and a grid, said device being characterized by a gradual variation of mutual conductance over a wide range with variation in the bias potential applied to 5 said grid, a frequency determining network coupled between said anode and grid, means for applying a suitable bias potential to said grid and for manually varying said bias, whereby the mutual conductance of said device is varied with- 10 out varying the frequency generated by said oscillation generator.

2. An oscillation generator for generating continuous, uninterrupted oscillations of substantially constant frequency comprising an electron discharge device of the variable mu type, having an anode, cathode and grid, said device being characterized by a gradual variation of mutual conductance over a wide range with variation in the bias potential applied to said grid, 15 a feedback circuit including frequency determining means connecting said anode and grid, a choke coil and a variable resistance in series between said grid and cathode, whereby the mutual conductance of said device can be adjusted 20 by means of said variable resistance without varying the frequency generated by said device. 25
